UNITED STATES PATENT OFFICE.

FRANK H. WAITE, OF LONG ISLAND CITY, NEW YORK.

BAFFLE BRICK.

Application filed July 5, 1921. Serial No. 482,307.

To all whom it may concern:

Be it known that I, FRANK H. WAITE, a citizen of the United States, residing at Long Island City, in the county of Queens and State of New York, have invented certain new and useful Improvements in a Baffle Brick, of which the following is a specification.

This invention relates to the construction 10 of arches for locomotive furnaces of the steam type and has for its principal object to provide a simple and efficient baffle brick which may be easily and quickly placed in its proper position when forming the arch and 15 when in its proper position will fit snugly against its supports, usually the water or air bars.

In the arches now commonly in use in locomotive furnaces it has been found from experience that the baffle bricks soon become 20 broken or otherwise injured because of the continuous jarring to the locomotive which is imparted to the bricks and because of the fact that they are not rigidly mounted in a 25 substantial manner, these bricks soon become cracked or utterly demolished and thus the efficiency of the arch is greatly reduced.

Another object of the invention is to provide 30 a baffle brick to be used in constructing the sides of the arch adjacent the furnace walls which bricks may be easily attached to the wall and detached therefrom when so desired.

In the drawing:—

35 Figure 1 is a sectional view taken through one wall of a furnace showing a fragmentary elevational view of one end of the arch,

Figure 2 is a top plan view of the structure disclosed in Figure 1,

40 Figure 3 is a section taken on the line 3—3 of Figure 1 looking in the direction of the arrow,

Figure 4 is a perspective view of the central baffle bricks and

45 Figure 5 is a perspective view of the side baffle bricks.

Referring to the drawing in detail it will be seen that 1 designates a side wall of a furnace while the bars 2 extending in a substantially parallel line thereto, represent water bars or air bars for the purpose of cooling the baffle bricks and also acting as a support therefor. The arch is formed by a plurality of baffle bricks which are placed 50 between the bars 2 and the side walls 1 of the furnace as is well known in the art. The central baffle bricks shown in the pres-

ent illustration of the invention are indicated by the numeral 3. These baffle bricks may be of any preferred shape and as here shown are rectangular in top plan and are 60 provided in their ends with channels 4. As shown to advantage in Figures 3 and 4 these channels 4 are deeper at one end than at the other. The deeper parts 5 of the channel are diagonally arranged in relation to 65 each other as clearly seen in Figure 3. Thus the central baffle brick disclosed in Figure 3 may be removed by rotating the same in a clockwise direction bringing the deeper portion 5 of the channels 4 in engagement with 70 the bar 2. When in this position the central bricks 3 may be easily removed as will be understood by those skilled in the art.

The side bricks 6 disclosed to advantage 75 in Figure 5 are each provided with a channel 7 at one end and a bayonet slot in the other end. The flanges 9 provided on the sides of the bricks 6 are oppositely disposed so that when the bricks are placed together there will be a locking engagement with 80 each other as indicated by the dotted lines in Figure 2. The bricks 6 are positioned in place by placing the channels 7 thereof in engagement with the bars 2 and the lugs 10 on the furnace wall 1 in engagement with 85 the entrance to the bayonet slot 8. When the lug is in the slot the brick will then be pushed so as to place the lug or the brick in such a position that the lug will be situated at the end of the slot opposite its opening 90 as will be readily understood.

Having thus described my invention what I claim as new is:—

In combination, a pair of walls, a plurality of bars situated between the walls, a plurality of bricks supported between the bars, each brick provided with channels at its ends, said channels being deeper at one of their ends and said deeper portions being diagonally disposed in relation to the bricks, and a plurality of bricks situated between the bars and the walls, lugs provided on the walls, said latter mentioned bricks each provided with a channel in one end for engaging one of the bars and a bayonet slot in its 105 other end for engaging one of the lugs.

In testimony whereof I affix my signature in presence of two witnesses.

FRANK H. WAITE.
